COMBINED CART AND SHELF FOR TELEVISION RECEIVERS

Walter Gusdorf, 8706 Florence, Brentwood, Mo.

Filed July 5, 1960, Ser. No. 61,225

Term of patent 3½ years

(Cl. D33—14)

FIG.1

FIG.3

FIG. 1 is a front elevational view of a cart and shelf for television receivers showing my new design;

FIG. 2 is a top plan view;

FIG. 3 is an elevational view from the left hand end of FIG. 1; and

FIG. 4 is a reduced perspective view from the front and showing the end opposite that in FIG. 3.

The broken line showings are for illustrative purposes only.

I claim:

The ornamental design for a combined cart and shelf for television receivers, substantially as shown and described.
